[57] **CLAIM**

The ornamental design for a polisher, as shown and described.

DESCRIPTION

FIG. 1 is a top left front perspective view of a polisher showing my new design.

FIG. 2 is a left side elevational view thereof. The right side elevational view thereof is an identical mirror image of the left side elevational view.

FIG. 3 is a front elevational view thereof.

FIG. 4 is a rear elevational view thereof; and,

FIG. 5 is a top plan view thereof.

The cord member is shown fragmented in FIGS. 1, 2, 4 and 5 in the drawing.

FIG. 1

FIG. 2

FIG. 4FIG. 3FIG. 5
